(57) **CLAIM**

The ornamental design for a vehicle, as shown and described.

DESCRIPTION

FIG. 1.1 is a perspective view of the vehicle;
FIG. 1.2 is a front view of FIG. 1.1;
FIG. 1.3 is a rear view of FIG. 1.1;
FIG. 1.4 is a top view of FIG. 1.1;
FIG. 1.5 is a right side view of FIGS. 1.1; and
FIG. 1.6 is a left side view of FIG. 1.1.
FIG. 2.1 is a perspective view of the vehicle, a second embodiment;
FIG. 2.2 is a front view of FIG. 2.1;
FIG. 2.3 is a left side view of FIG. 2.1;
FIG. 2.4 is a rear view of FIG. 2.1;
FIG. 2.5 is a right side view of FIGS. 2.1; and
FIG. 2.6 is a top view of FIG. 2.1.
The broken lines, shown in the line drawings, illustrate portions of the vehicle that form no part of the claimed design. The ghosted or low contrasted showing of the vehicle is provided for the purposes of illustrating portions that form no part of the claimed design.

1 Claim, 11 Drawing Sheets
